UNITED STATES PATENT OFFICE

FLOYD L. PALMER, OF WAVERLEY, MASSACHUSETTS, ASSIGNOR TO LUNDIN
ELECTRIC & MACHINE CO., OF BOSTON, MASSACHUSETTS

INCANDESCENT LAMP SOCKET REMOVER

Application filed May 5, 1932. Serial No. 609,446.

My present invention relates to incandescent lamp socket removers and more particularly to a lamp socket remover which may be used in high places ordinarily not accessible by hand. In a tool of this character, it is necessary to have a positively operated mechanism which may easily be placed about the socket and which when released will lock about the socket to prevent slipping or otherwise releasing the socket from engagement until the operator is ready to do so. In my present device I have designed such a tool provided with a locking mechanism which will close the jaws of the cage portion around the socket and remain in a fixed locked position even though the jaws are not perfectly seated about the socket due to the fact that the jaws automatically are allowed to close but are prevented from reopening until the operator is ready to release the tool.

The principal object of my invention is an improved incandescent lamp socket remover.

Another object is a positive locking mechanism which locks the jaws in one direction and which will release said jaws and open them at any desired time.

Other objects and novel features comprising the construction and operation of my invention will be apparent as the description of the same progresses.

In the drawing illustrating the preferred embodiment of my invention, Fig. 1 illustrates a side elevation of the tool, the cover plate normally covering the locking mechanism having been removed. The full lines show the tool with the jaws in a nearly closed position and the broken lines showing the tool in a fully opened position.

Fig. 2 is a fragmentary side elevation similar to Fig. 1 but showing the locking mechanism in an interlocked position just prior to the opening of the jaws as shown in the broken line position of Fig. 1.

Referring more in detail to the drawing, with particular reference to Fig. 1, the tool comprises in general an upper cage element divided into a fixed jaw portion 8 and a pivoted jaw portion 9, each of said jaw members comprising a number of elements hereinafter

referred to more in detail. 10 indicates a shallow box-like casing provided at the bottom side with a socket portion 11 in which is mounted tubular member 12 secured therein by means of screws 13. The tubular member 12 may be of any desired length and may be composed of extension members attached lower down (not shown in drawing) for the purpose of operating the tool at any desired distances. Attached to the upper right hand side of the casing 10 and integral with the casing is a supporting frame member 14 the upper portion of which terminates in a hollow semi-circular collar portion 15 comprising the fixed jaw portion 8. The collar portion 15 is further provided with lug members 16 to which are attached substantially flat flexible bar members 17, the bottom ends of said bar members being solidly attached to the upper side of the casing 10. The opposite side of this fixed jaw portion is provided with a duplicate set of bar members 17, being attached in a similar manner to the casing 10 and the opposite side of the collar 15. The supporting frame member 14 is centrally disposed between the bar members located on either side of the tool. A movable jaw member 9 is pivoted at 18 about a stud 19 which is solidly attached to the back 20 of the casing 10. The movable jaw member 9 is constructed identically the same as the said first jaw member comprising the central supporting member 14a, bars 17a, and collar 15a. Both the members 14 and 14a are provided with horizontal strap members 21 and 21a, to which the bar members 17 and 17a are riveted as shown in Fig. 1.

The adjustable jaw member 9 is provided with a downwardly projecting portion 22 having the recessed inner surface 23 on a one side and a pin 24 solidly embedded therein over which is placed a slotted link member 25. One end of the link member is pivoted to a pin 26 embedded in a cam member 27 which forms a portion of the lever 28 which is further provided with a hub portion 29 pivoted at 30 about a stud 31 solidly attached to the back 20 of the casing 10. The cam portion 27 is internally slotted at 32 for the purpose of receiving the looped end of a spring wire 100

32a which is a continuation of a coiled spring 33 anchored in the tubular member 12 at its lower end by means of the pin 34. The upper looped end of the wire 33 being secured 5 by means of the pin 26 located in the cam portion 27. The sides of the casing 10 are cut away in the upper left hand corner as indicated at 35 to allow the movable jaw member to swing in to the broken line position shown 10 in Fig. 1. A cover plate 36 comprising a flat rectangular member having the general outline of the casing 10 is provided for the purpose of keeping the locking members in place and is secured to the casing 10 by means of 15 screws, not shown, adapted to thread into the threaded orifices 37 in the center of the stud members 19 and 31. The link member 25, upper surface 37 of the movable jaw member 9, the face of the studs 19 and 31, as well as the 20 hub 30 of the lever are all in the same plane as the upper surfaces 38 of the side portions of the casing 10 and the inner surface of the lower plate 36 comprises the side bearing for said elements.

25 In operation, the lever 28 is pulled down by either a cord or a wire 39 which is controlled by the hand of the operator from a point below and as it reaches the position shown in Fig. 2, the cam 27 which locks the jaws has 30 now passed upwardly into the position shown in Fig. 2 and the slotted link 25 has reached the end of its travel on the pin 24 and by continuing the downward movement of the lever arm 28 into a broken line position of Fig. 1, 35 the movable jaw is pulled open by the link 25 into the position shown by dotted lines in Fig. 1. In this position the jaw members may be passed over an incandescent lamp and the collar member 15a placed against the side of 40 a lamp socket. The operator now releases a lever 28 and the spring 33 which is under tension at this point draws down the cam 27 and brings the movable jaw member 9 into contact with the other side of the lamp socket. The 45 engagement of the cam 27 with the lower right hand side 22 of the movable jaw member 9 prevents the movable jaw member from opening again but may allow it to close further should it not be properly seated around 50 the socket in the first instance. Due to this flexibility of locking range, the diameters of the sockets on which the tool may be used may vary within wide limits with the tool functioning properly.

55 Having thus described my invention what I claim is:

1. An incandescent lamp socket remover comprising a casing adapted to house pivoted operative members, a split cage member 60 located above said casing comprising a fixed jaw member integral with said casing and a movable jaw member having a lower depending portion pivoted within said casing, said fixed jaw portion consisting of a single supporting frame member terminating in a semi-

70 circular collar portion, said collar portion having lug members cast on the lower edge thereof, a plurality of vertical flexible bar members having their lower ends fixed to the top of said casing and their upper ends attached to said lug members by means of screws, a centrally and horizontally disposed flexible bar member attached to said supporting frame member and said vertical bar members, said movable jaw member being similarly constructed with respect to supporting frame member, vertical bars, and horizontal bars, a cam lever pivoted within said casing and having an operating lever extension arm protruding therefrom and adapted to engage on its cam surface with one side of a depending portion of one half of said cage located within said casing, a link member pivoted to said cam and slidably attached to the side of said depending member, a tubular base member attached to the bottom of said casing, a tension spring attached within said tubular member at one end and anchored to said cam at its other end.

75 80 85

90 95 100 105

2. An incandescent lamp socket remover consisting of a box-like casing, a cage member located at the upper side of said casing and a tubular member located at the under side of said casing, said cage member comprising a fixed jaw portion integral with said casing and a movable jaw portion pivoted on said casing, a cam lever pivoted within said casing having a protruding extension arm, said cam lever adapted to engage on its cam surface with the side of a lower depending portion of said movable jaw member, a tension spring located within said tubular member having one end attached to said tubular member the other end anchored to said cam lever.

110 115 120 125

3. An incandescent lamp socket remover comprising a casing adapted to receive pivoted locking members, an upper split cage member adapted to surround the lamp and and socket and engage said socket, said cage comprising two symmetrical halves one of which is solidly fixed to said casing and the other of which is pivoted within said casing, a cam lever pivoted within said casing and having an operating lever extension arm protruding therefrom and adapted to engage on its cam surface with one side of a depending portion of a pivoted half of said cage located within said casing, a link member pivoted to said cam and slidably attached to the side of said depending member, a tubular base member attached to the bottom of said casing, a tension spring attached within said tubular member at one end and anchored to said cam lever at its other end.

130

4. An incandescent lamp socket remover comprising a casing adapted to house pivoted locking members, a split cage member located above said casing comprising a fixed jaw member, said fixed jaw member being

integral with the said casing, and a movable jaw member having a lower depending portion pivoted within said casing, each of said jaw members provided at their upper extremities with semi-circular collar portions adapted to surround and engage said lamp socket, a cam lever pivoted within said casing and having an operating lever extension arm protruding from said casing, said cam lever adapted to engage on its cam surface with one side of said depending portion of movable jaw member, a link member pivoted to said cam and slidably attached to the side of said depending member, a tubular base member attached to the bottom of said casing, a tension spring attached within said tubular member at one end and anchored to said cam at its other end.

5. An incandescent lamp socket remover comprising a casing adapted to house pivoted operative members, a split cage member located above said casing comprising a fixed jaw member, said jaw member being integral with said casing, and a movable jaw member having a lower depending portion pivoted within said casing, each of said jaw members provided at their upper extremities with complementary collar portions adapted to pass over and engage said lamp socket, a cam lever pivoted within said casing and having an operating lever extension arm protruding from said casing, said cam lever adapted to engage on its cam surface with an inner cam surface of said depending portion of the movable jaw member, a link member pivoted to said cam and slidably attached to said depending member, a tubular base member attached to the bottom of said casing, a tension spring located within said tubular member, said tension spring having the lower end fastened within tubular member and the upper end internally anchored to said cam, said cam surface and said depending surface having centrally disposed internal channels provided for tension spring extremity to follow cam travel.

In testimony whereof I have affixed my signature.

FLOYD L. PALMER.
